UNITED STATES PATENT OFFICE.

FRED W. STEUER, OF BOSTON, MASSACHUSETTS, ASSIGNOR TO COOK LABORATORIES, INC., A CORPORATION OF DELAWARE.

HYPODERMIC SYRINGE.

Application filed March 25, 1925. Serial No. 18,099.

This invention relates to hypodermic syringes of the type employing medicament-dispensing cartridges or containers, and among other objects aims to provide an improved 5 construction of syringe adapted to be opened laterally for lateral insertion of the cartridge.

The invention may be understood by reference to one illustrative embodiment shown in the accompanying drawings, in which:

10 Fig. 1 is a side elevation of the syringe shown ready for use;

Fig. 2 is an enlarged elevation of the principal parts of the syringe shown open for loading;

15 Fig. 3 is an end elevation of the syringe as shown in Fig. 2.

Fig. 4 is an enlarged longitudinal sectional view showing the medicament cartridge in position.

20 Fig. 5 is a section on line 5—5 of Fig. 4.

It is to be understood that the illustrative embodiment shown in the drawings is simply a preferred form of the invention; and that in the following explanation of that specific

25 form, the described details of structure and organization are merely exemplary.

The syringe barrel comprises two complementary barrel sections 6, 7, each of which is shown as semi-cylindrical, hinged together longitudinally as at 8 to permit opening thereof for loading the syringe with a medicament cartridge. The cartridge shown consists of a glass tube 9 sealed at opposite ends by a readily pierceable plug 10 and a 30 slidable plug 11, the latter designed to be pushed by the plunger rod 12 of the syringe to dispense the medicament through the syringe needle 13; said cartridge exemplifying a medicament package whose interior volume is contractible.

In the specific syringe shown, either barrel section may provide an open tray for reception of the cartridge, as will be understood from Fig. 2; however, as a matter of convenience, the cartridge will be laid most frequently in barrel section 6, which carries the plunger rod. After the cartridge is in place, the barrel section 7, which then serves as a lid, is closed, and the two sections are held together by a sleeve lock 14 at the plunger end

of the instrument, thus securing the cartridge. The sleeve lock 14 is shown swiveled on a barrel head 15 which is movable longitudinally by means of a hollow screw 16 secured thereto and projecting therefrom and threaded 55 within a ring 17 secured to the end of the barrel section 6. A knurled bead 18 on barrel head 15 facilitates rotation of said head to work the screw and thereby advance or retract the sleeve lock, which is constructed 60 and arranged to enclose the ends of the barrel sections. Through the hollow screw the plunger rod 12 may slide.

At the forward end of screw 16 a flange 19 is formed for engagement with butt end of 65 the cartridge (Fig. 4). The opposite end of barrel section 6 has a stop or abutment 20 which serves to engage the front end of the cartridge so as to retain the cartridge until the barrel is closed. In using the syringe, 70 it is desirable to force the cartridge in the direction of the needle, not only to complete the piercing of its end plug 10 by means of the needle, but also to prevent objectionable looseness of fit of a sub-standard cartridge, 75 and to press the resilient end plug 10 against the head 21 provided on barrel section 7 to insure a tight seal at that end of the cartridge. Obviously, the syringe may hold cartridges of various sizes. The needle- 80 carrying head 21 is slotted as at 22 to receive abutment 20 when the syringe is closed. However, as will be understood from Fig. 3, the abutment does not interfere with the insertion of the needle into the pierceable end 85 plug 10, which may be done after the cartridge is inserted in the syringe.

Obviously, the present invention is not restricted to the particular embodiment thereof herein shown and described. Moreover, it 90 is not indispensable that all the features of the invention be used conjointly, since they may be employed advantageously in various combinations and sub-combinations as defined in the claims.

What is claimed is:

1. A hypodermic syringe comprising, in combination, a barrel; said barrel comprising longitudinally hinged sections to permit lateral opening for convenient insertion 100

of a cartridge of medicament; a needle secured at one end of the barrel and extending into it; and a locking sleeve constructed and arranged to be moved over the ends of the 5 barrel sections when brought together to hold the barrel sections in cartridge enclosing position.

2. A hypodermic syringe comprising, in combination, a longitudinally divided barrel 10 comprising longitudinally hinged sections; and means for locking the hinged barrel sections together consisting of a hollow sleeve fitting over both sections to lock the barrel when closed, and means connected with the 15 sleeve and screw-threaded on one of the barrel sections to move said sleeve longitudinally.

3. A hypodermic syringe comprising, in combination, a longitudinally hinged barrel providing two relatively movable barrel sections; one of said barrel sections having an 20 abutment for a cartridge of medicament; means for locking the barrel sections together; a plunger; and means constructed and arranged to force the cartridge against said 25 abutment, before operation.

4. A hypodermic syringe comprising, in combination, a sectional longitudinally hinged barrel, the sections whereof are hollow to fit about a cartridge of medicament; a 30 syringe head carried on one of said barrel sections at the end thereof and movable longitudinally of said section by means of screw-threads; and a hollow sleeve swiveled on the syringe head at one end thereof and constructed and arranged to be moved over the 35 adjacent ends of the juxtaposed barrel sections when the syringe head is rotated in one direction, thereby to lock the barrel sections in cartridge-enclosing position.

40 5. A hypodermic syringe comprising, in combination, a sectional longitudinally hinged barrel, the sections whereof are hollow to fit about a cartridge of medicament; one of said sections having a syringe head at one 45 end thereof, and means projecting from the syringe head upon which a double-pointed hypodermic needle may be secured; another of said barrel sections having an abutment at the corresponding end against which the cartridge may be thrust; said syringe head having a lateral slot to receive said abutment whose form and dimensions are such that inward thrusting of the needle to pierce the end of the cartridge is not interfered with 55 when the sections are brought together; means carried by the barrel section having the abutment constructed and arranged to engage the cartridge to thrust it against the abutment and hold it on said barrel section; 60 and means to lock the barrel sections together in cartridge-enclosing position.

65 6. An instrument of the class described comprising, in combination, a cartridge-holder comprising complementary longitudinally hinged sections, one of said sections

having a breech head and plunger and associated means embodying an axially adjustable screw for locking the sections in closed or cartridge-holding position.

7. An instrument of the class described, 70 comprising a cartridge-holder having at its fore end a means for holding a cartridge piercing cannula and an abutment for the fore end of the cartridge and having at its breech end a plunger to enter the cartridge, 75 and a means to press the cartridge against said abutment before operation of the plunger, said cartridge-holder comprising complementary longitudinally hinged sections.

8. In a cartridge syringe, a cartridge- 80 holding and operating instrument having in its breech end a cartridge-operating plunger and having its fore end constructed to provide a cartridge abutment and to accommodate a cartridge-piercing cannula, said instrument embodying longitudinally-hinged complementary cartridge-enclosing sections and a longitudinally movable locking sleeve adapted to cooperate with said sections to 85 lock the instrument in closed operative condition.

9. In a cartridge syringe, a cartridge- 90 holding and operating instrument having in its breech end a cartridge-operating plunger and having its fore end constructed to provide a cartridge abutment and to accommodate a cartridge-piercing cannula, said instrument embodying longitudinally-hinged complementary cartridge-enclosing sections and having axially adjustable means to force 95 the cartridge against said abutment and to lock the instrument in closed operative condition.

10. In a cartridge syringe, a cartridge- 100 holding and operating instrument having in its breech end a cartridge-operating plunger and having its fore end constructed to provide a cartridge abutment and to accommodate a cartridge-piercing cannula, said instrument embodying longitudinally-hinged complementary cartridge-enclosing sections and having in its breech end an axially movable member in which the plunger is mounted, adapted to lock the instrument in closed 105 operative condition.

11. In a cartridge syringe, a cartridge- 110 holding and operating instrument having in its breech end a cartridge-operating plunger and having its fore end constructed to provide a cartridge abutment and to accommodate a cartridge-piercing cannula, said instrument embodying longitudinally-hinged complementary cartridge-enclosing sections and having in its breech end screw actuated 115 means to force the cartridge against said abutment and to lock the instrument in closed operative condition.

12. In a cartridge syringe, a cartridge- 120 holding and operating instrument having in its breech end a cartridge-operating plunger 125

and having its fore end constructed to provide a cartridge abutment and to accommodate a cartridge-piercing cannula, said instrument embodying longitudinally-hinged complementary sections, a screw in which the plunger is mounted connected with one of said sections and adapted to bear on the butt end of the cartridge to force it against said abutment, and means associated with said screw to lock the instrument in closed operative condition. 10

In testimony whereof, I have signed my name to this specification.

FRED W. STEUER.
